[57] CLAIM

The ornamental design for an electrical connector plug, as shown.

DESCRIPTION

FIG. 1 is a top plan view of an electrical connector plug showing my new design.

FIG. 2 is a right side elevational view of the electrical connector plug of FIG. 1.

FIG. 3 is a bottom plan view of the electrical connector plug.

FIG. 4 is a front elevational view of the electrical connector plug.

FIG. 5 is a rear elevational view of the electrical connector plug.

The wires are shown in broken lines for illustrative purposes only.

FIG. 1**FIG. 2****FIG. 3****FIG. 4****FIG. 5**
